UNITED STATES PATENT OFFICE.

SAMUEL PIERCE, OF TROY, NEW YORK.

STEAM-BOILER.

Specification of Letters Patent No. 23,490, dated April 5, 1859.

To all whom it may concern:

Be it known that I, SAMUEL PIERCE, of Troy, county of Rensselaer, and State of New York, have invented a new and useful 5 Improvement in Steam-Boilers; and I do hereby declare that the following is a full and exact description thereof, reference being had to the accompanying drawings, making part of this specification, in which, 10 Figure 1, is a vertical longitudinal section through the center of a locomotive boiler, with my improvement applied, Fig. 2, a vertical cross section at the line x, x , of Fig. 1. Fig. 3, a vertical longitudinal section 15 through center of one of the air supplying tubes, and, Fig. 4, a vertical cross section at line y, y , of Fig. 3.

The same letters indicate like parts in all the figures. 20 It has long been known that the discharge of jets of atmospheric air above the fire to consume the combustible gases evolved from the fuel, conduces greatly to the economy of fuel, as without this a very large portion of 25 the combustible matter escapes from the chimney in the form of smoke and carbonic oxid: but serious difficulties have been experienced in the introduction of the jets of air. If the jets are introduced too far from the 30 surface of the fire, the required ignition will not take place, and if applied so near, and in such manner as to induce the thorough commingling of the atmospheric air and combustible gases at a sufficiently high temperature 35 to insure thorough combustion, the apparatus employed for the discharge of the jets of air is exposed to such a high temperature as to be thereby destroyed in a very short time. For these reasons very little use 40 has been made of this method of economizing fuel and of avoiding the nuisance of smoke.

The object of my said invention, particularly in view of the growing necessity for 45 the burning of coal, is to avoid the difficulties heretofore experienced in the combustion of the inflammable gases, and to this end my invention consists, in the employment of perforated air tubes in the fire 50 chamber, and above the fuel, which tubes receive atmospheric air from outside the fire chamber and discharge it in numerous small jets among the gaseous products of combustion, when the said perforated air tubes are combined with water tubes surrounding them and connected with the water

legs, or other water spaces of the boiler, and also connected with the air tubes inside, by hollow stay bolts forming passages for the discharge of the numerous jets of atmospheric air among the gaseous products of combustion and when the air and water tubes, so combined, are arranged in such manner within the fire chamber as to insure the thorough commingling of the jets of air 65 discharged with the gaseous products of combustion, without constituting any obstacle to the feeding or managing of the fire.

In the accompanying drawings my said invention is represented as applied to that 70 class of boilers known as locomotive boilers: but it will be obvious that it can be applied in the same manner to any other class of steam boilers. The fire chamber A, of the said boiler, is surrounded in the usual manner with water legs or spaces b, c, d, at the sides, front, and back communicating with the water in the body of the boiler, f, through which the smoke flues D, pass horizontally from the fire chamber to the smoke 80 box E, leading to the chimney.

Within the fire chamber, and above the fire, I place a series of tubes I, extending from the front to the back water leg or space and in an inclined direction: but, instead, 85 they may be placed across the fire chamber in an inclined position and communicating with the two side water legs, or they may be placed both longitudinally and transversely, or they may be otherwise arranged as will be presently stated. Each one of these tubes is double, consisting of an outer tube I, attached to the inner plates of the water legs and communicating with the water in the legs: and the inner tube I' 90 is of less diameter so as to leave a sufficient space between the two for the free circulation of water: one end I² is closed, and the other passes through the water leg and is secured to the outer plate of the boiler and 100 communicates with the atmosphere outside; or if desired with a suitable blowing apparatus.

Both the inner and the outer tubes are connected by numerous hollow stay bolts i, i, 105 which not only hold the two tubes concentric with each other, but form numerous small passages for the air, which, entering the inner tube from the outer atmosphere, or form a suitable blower, is discharged in 110 numerous small jets among the gaseous products of combustion above the fire, and

before these products have traveled so far as to lose the intensity of heat which is necessary to insure combustion when mingled with the jets of air. As the spaces between 5 the inner and the outer tubes communicate at both ends with water in the boiler, and these tubes are inclined, the heat, to which they are exposed, will cause a rapid circulation of the water which will carry off the 10 heat and prevent the metal from being injured notwithstanding the close proximity to the fire. In this way I am enabled to supply the air to the combustible gases directly over the fire, where it will be sure to 15 ignite, and thoroughly consume the combustible gases, and at the same time to protect the apparatus, employed for this purpose, from the injurious action of the required intense heat; and although I have de- 20 scribed the said tubes as being inclined, to insure the circulation of the water by which they are protected, against the injurious action of the intense heat, I have only done so because I deem that the best mode of ap- 25 plication; but any other mode of connection which will insure the circulation of the water through the space, between the inner and the outer tubes, may be substituted, and with this view I have contemplated placing 30 the said double tubes in a horizontal position, and connecting the space between the inner and the outer tubes with the water in the upper part of the boiler, by branch tubes to effect a connection of such spaces 35 with the water in the boiler at different levels, that the water may enter such spaces at the lower level and, by rarefaction, be made to pass through and be discharged,

with the steam generated therein, at a higher level; other and equivalent modes of application may be substituted. 40

I do not claim as of my invention the application of air, in numerous small jets, by means of perforated tubes in the fire chamber of steam boilers. Nor do I wish to 45 limit my claim to any precise position of the tubes within the fire chamber, so long as they are placed above the fire to discharge the jets of air among the gases evolved where they are at an intense 50 heat. Nor do I claim the use of hollow stay bolts for connecting tubes or other vessels. Nor do I claim the circulation of water to prevent metal from being injured by the action of intense heat. Nor 55 do I claim a series of water tubes embodying air tubes when such series are made to constitute a water table; as shown in the application of the patent granted Dec. 22nd 1857 to B. L. Griffith; but 60

What I do claim as my invention and desire to secure by Letters Patent, is—

The employment of air tubes placed within the fire chamber of a steam boiler, substantially as described, in combination with 65 the surrounding water tubes connected at both ends with the water spaces of the boiler and connected with the inner air tubes by means of hollow stay bolts, where the air and water tubes so combined are arranged 70 substantially as specified for the purpose set forth.

SAMUEL PIERCE.
